CLAIM

The ornamental design for a disposable absorbent pants with containment system, as shown and described.

DESCRIPTION

FIG. 1 is a perspective view of a disposable absorbent pants with containment system in accordance with one aspect of the invention.

FIG. 2 is a cross-sectional view of the disposable absorbent pants with containment system of FIG. 1 taken along the line 2-2.

FIG. 3 is a top plan view of the disposable absorbent pants with containment system of FIG. 1.

FIG. 4 is an enlarged view of the portion of the disposable absorbent pants with containment system marked 4 in FIG. 3; and,

FIG. 5 is a cross-sectional view of the disposable absorbent pants with containment system taken along the line 5-5 in FIG. 4.

The broken lines in the drawings depict environmental subject matter and form no part of the claimed design.
